INK ROLL STRUCTURE

Robert G. Chollar, Dayton, Ohio, assignor to The National Cash Register Company, Dayton, Ohio, a corporation of Maryland

Application December 29, 1941, Serial No. 424,750

3 Claims. (Cl. 91—67.8)

This invention relates to an improved ink supply roll structure for inking ribbons, electroplates, type, or any other similar printing medium used in printing records or data.

A specific object of the invention is to provide an ink supply roll of a highly absorbent quality, and one which can absorb and retain a large supply of ink.

Another specific object of the invention is to provide an ink supply roll which is made of unsized paper made of cellulose fibers and which is porous, bulky, and of low finish, and which paper is commonly known as "blotting paper."

With these and incidental objects in view, the invention includes certain novel features of construction and combinations of parts, the essential elements of which are set forth in appended claims and a preferred form or embodiment of which is hereinafter described with reference to the drawing which accompanies and forms a part of this specification.

In said drawing:

Fig. 1 illustrates one application of the invention, in which a wick is constructed to contact the inking roll at one edge thereof, as shown in Fig. 3.

Fig. 2 shows the laminated construction of the ink supply roll.

Fig. 3 is a detail view of the application illustrated in Fig. 1.

General description

The invention disclosed herein comprises a new means for supplying ink to printers, and is illustrated herein as used in business machines and the like. Machines of this character are adapted to print many types of records, such as receipts issued from cash registers, detail or audit strips, ledger cards, pass books, and the like. Some impressions are made through the medium of inking ribbons, some direct from inked type and electros. In either case, it has always been a problem to keep the ribbon, or other inking medium, in proper condition to provide good and uniform printed records over a long period of time. In the past, an ink-saturated felt supply roll was commonly used. When ink ribbons were used, the ribbon was threaded in the machine in such a way that it passed over and around the felt supply roll, thus replenishing the supply of ink to the ribbon. When the impressions were made direct from the type or electro, the felt roll was passed over the type to ink the face thereof. This was a satisfactory inking medium; however, the felt rolls have certain in-

herent objectionable features. The principal objectionable features inherent in a felt roll are that the initial prints are so much wetter than subsequent prints, and that the excess inking of the ribbon or type extracts more ink than is necessary for such initial prints, thus prematurely exhausting the ink from the supply roll. Therefore, uniform prints for an extended period of time are impossible, thus making it necessary to replace the felt rollers at too frequent intervals. These objectionable features have been overcome by constructing the ink supply rolls of soft spongy paper of an absorptive characteristic, which is porous, bulky, and of a low finish, commonly known as "blotting paper." The particular grade of "blotting paper" which is satisfactory for ink supply rolls depends on the hardness and the nature of the inking pressure, and the range of paper found satisfactory comes within the following specifications: 60-140 pounds per 500 sheets, size 19" x 24", .021" thick, 16-18 Mullen strength.

In constructing the ink supply rolls of the above quality, it was found convenient to use stock "blotting paper" and stamp, or otherwise cut, disks from standard sheets, assemble these disks on an axle or support, and compress the disks into a roll to resemble a solid roll of paper. After the roll is assembled, its periphery is ground, lapped, or burnished to a smooth surface. The smooth surface and the lack of resiliency of the paper roll, when compared to the best grade of felt roll, are the qualities that make the paper roll more suitable than felt rolls for re-inking ribbons. The smooth and comparatively hard surface of the paper roll is not so "spongy" as the surface of a felt roll, and the pores of the roll are fine enough and the surface is hard enough so that pressure of the ribbon and the capillary action of the ink do not cause an oversupply of ink to reach the surface, thus supplying only the required quantity of ink at the surface and preventing overinking at spots of rest of the ribbon.

Another advantage of the use of "blotting paper" for ink supply rolls over felt rolls is that the "blotting paper" absorbs more ink per cubic volume. The comparison of felt to paper of the above specification in their capacity to absorb ink is as follows:

1 cubic inch of felt absorbs .53 cubic inch of ink.
1 cubic inch of "blotting paper" absorbs .70 cubic inch of ink.

The comparative results in actual use reveal that .70 cubic inch of ink in a "blotting paper"

roll gives 150 satisfactory printed cash register receipts to 100 printed receipts from .53 cubic inch of ink in a felt ink supply roller. The reason for this is that the initial prints from felt rolls are wetter than the initial prints from paper rolls, and therefore more ink is used than is necessary for obtaining a good print. This is due to the fact that the "blotting paper" rolls can be ground to a smooth surface, and the amount of ink on this smooth surface is more uniform than that on the spongy and soft surface of a felt roll. The amount of ink that rises to the surface of the "blotting paper" roll through capillary action can be regulated by the smoothness to which the paper roll is ground, lapped, or burnished. This advantage cannot be attained in felt rolls, because felt is so porous that the inking surface cannot be ground to a smooth finish, and for this reason the felt roll must of necessity have a coarse surface, which sometimes acts to smear the impression due to overinking, particularly when the roll is saturated when first installed. This obviously also means that a waste of ink is had and the roll is drained of its ink supply more quickly than the printing requirements demand. This waste of ink, taken with the fact that the felt cannot absorb as much ink as a "blotting paper" roll, illustrates why the novel roll disclosed herein has a longer life.

The "blotting paper" roll can be used in machines where it is not desired to constantly replace the ink used therefrom. In some machines in use, the felt roll can be replaced by a "blotting paper" roll. In other machines, a reservoir or "ink well" can be built into the machine and a wick interposed between the reservoir and the roll, which wick constantly replaces the ink taken from the ink roll. Many different forms of wicks can be used.

Another use for the novel ink roll is in machines in which it is not convenient to replace the felt ink roll. In such uses, the novel roll is arranged to contact the felt roll and transfer the ink from the paper roll to the felt roll during the machine operation, when the two rolls rotate upon each other.

In this use, the paper roll has been found particularly efficient in supplying the correct amount of ink to maintain the felt roll in proper inking condition. This result is due to the smooth surface and the resultant capillary action of the ink rising to the smooth surface, which action never provides more ink than is necessary to keep the felt roll in good inking condition. When a rough surface felt roll is used for this purpose, overinked areas result in places where capillary action provides an oversupply of ink, thus making uniform printing impossible.

In the machines where the paper ink supply roll is used, the paper roll is normally held out of contact with the felt roll while the machine is at rest, and is brought into contact therewith when the machine is operated at the desired time, by any mechanical expedient. This mechanical construction is provided to prevent overinking the felt rolls at the point of contact, which would take place if such a contact were maintained while the machine is at rest.

A wick may be held in contact with the paper roll to maintain the paper roll at the saturation point at all times.

Detailed description

The preferred construction of the "blotting paper" roll is best illustrated in Fig. 2. Disks 10 are cut from sheets of "blotting paper" of the specifications given above and are threaded on an arbor or support 11. The number of disks 10 used for each roll depends on the length of roll desired. After the proper number of disks 10 has been assembled on the arbor 11, they are compressed against one another and held in place by a disk or flange 12 at each end of the arbor 11, which flanges may be held in proper spaced relationship on the arbor 11 by any desired means. Pins 13 are shown herein for illustrating the invention. The diameter of the flanges 12 can vary with the requirements and use of the roll. For example, they may be of a greater diameter than the paper roll, as shown in Fig. 1, or they may be of the same diameter as the paper roll, as shown in Fig. 2. If a special use should require it, the flanges can be made of slightly smaller diameter than the diameter of the roll.

Figs. 1 and 3 illustrate a wick 14 so constructed and arranged that an edge 15 thereof contacts the roll 10. The lower end of the wick 14 is immersed in the ink 16 contained in the supply well 17. The wick 14 is made of any suitable material to convey the ink to the paper roll 10 so that the roll always contains an ample supply of ink. When an inking ribbon is used, the ribbon 18 is fed around the inked roll 10 and absorbs ink from the surface thereof.

In the disclosure herein, the roll 10 is illustrated and described as being made from disks of commercial "blotting paper" of certain specifications. However, the novelty of the invention is not limited to a roll made up of disks of "blotting paper," since a solid roll formed of paper pulp of cellulose fibers comes within the scope of the present invention.

The invention has also been illustrated and described as used in business machine printers. It is not the intention to limit the use of the invention to such machines, as it is obvious that the invention can be utilized in many other machines where printing is performed.

While the form of the invention herein shown and described is admirably adapted to fulfill the objects primarily stated, it is to be understood that it is not intended to confine the invention to the form or embodiment disclosed, for it is susceptible of embodiment in various other forms all coming within the scope of the claims which follow.

What is claimed is:

1. An ink supply roll consisting of a plurality of disks of unsized paper having a high quality of absorptivity, said paper being porous, bulky, and of low finish; and means to compress the disks against one another.
2. An ink supply roll comprising a plurality of disks of "blotting paper"; and means to maintain the disks in close contact with one another.
3. A roll comprising a plurality of disks of unsized, porous, bulky, and low-finish paper arranged in close contact with one another; and a flange at each end of the roll to maintain the disks in such contact with each other, said plurality of disks being saturated with ink to form an ink supply roll.

ROBERT G. CHOLLAR.
